UNITED STATES PATENT OFFICE.

WILLIAM B. MASON AND LURAL S. RYAN, OF LAMAR, MISSOURI.

BED-TRAY.

1,343,636.

Specification of Letters Patent. Patented June 15, 1920.

Application filed October 30, 1919. Serial No. 334,405.

To all whom it may concern:

Be it known that we, WILLIAM B. MASON and LURAL S. RYAN, citizens of the United States, residing at Lamar, in the county of Barton, State of Missouri, have invented 5 certain new and useful Improvements in Bed-Trays; and we do hereby declare the following to be a full, clear, and exact description of the invention, such as will enable others skilled in the art to which it applies 10 to make and use the same.

This invention relates to new and useful improvements in attachments for beds, and particularly to tray attachments therefor.

15 One object of the present invention is to provide a novel and improved device of this character which is simple in construction, easy and cheap to manufacture, and which is durable and strong.

20 Another object is to provide a novel and improved means for detachably securing the tray to the post of the bed and whereby the tray may be easily and quickly moved into and out of operative position for the 25 convenience and comfort of the patient.

A further object is to provide a novel and improved tray which has means for supporting a cuspidor or sputum cup.

Other objects and advantages will be apparent from the following description when 30 taken in connection with the accompanying drawing.

In the drawing:

Figure 1 is a side elevation of the improved tray shown in connection with a bed 35 post.

Fig. 2 is an end view of the same.

Fig. 3 is a horizontal sectional view 40 through the bed post, looking upwardly, and taken on the line 3—3 of Fig. 1.

Referring particularly to the accompanying drawing, 10 represents the post of the bed, on which the invention is applied. Engaged around the post is a clamping ring 45 11 to which is secured the upper end portion of a vertical flat metal bar 12. Secured to the lower end portion of this bar is a ring segment 13 which partially embraces the lower portion of the post, as clearly seen in

the drawing. The upper and lower ends 50 of the bar 12 are turned outwardly in a direction away from the bed post, and in parallel relation to each other, as shown at 14, said portions being vertically apertured to receive the vertical stem 15 of the tray 55 supporting arm 16, and in which said stem is rotatable. Secured to the stem, above the upper portion 14, and resting thereon, is a collar 17, which serves to support the tray supporting arm in proper position for 60 horizontal swinging movement.

Secured to the upper face of the outer end of the arm 16 is the tray 18, the same being formed with a peripheral rim or flange 19. A vertical bar 20 has its upper and 65 lower ends turned angularly from the body of the bar, in parallel relation, as shown at 21, the upper one being secured to the center of the bottom of the tray, while the lower one is secured to the bottom of the lower 70 supplemental tray 22, disposed below the tray 18. This lower tray is formed with a peripheral flange 23, and is arranged to support a cuspidor or sputum cup for the use 75 of the patient.

What is claimed is:

A tray attachment for a bed post, comprising a vertical bar having its upper and lower ends turned at an angle to the body and vertically apertured, a clamping ring 80 secured to the upper end of the bar, a ring segment secured to the lower end of the bar, a tray supporting arm having a stem disposed for rotation in the said apertured ends of the bar, a tray secured to the outer end 85 of the arm, a bar having its upper and lower ends turned angularly from the body, the upper end being secured to the bottom of the tray, and a supplemental tray disposed below the first tray and secured to the other 90 angularly turned end of the second bar.

In testimony whereof, we affix our signatures, in the presence of two witnesses.

WILLIAM B. MASON.

LURAL S. RYAN.
